(57) **CLAIM**

We claim the ornamental design for a fluid applicator tip, as shown and described.

DESCRIPTION

FIG. 1 is a perspective view of a fluid applicator tip; FIG. 2 is a front view of the fluid applicator tip of FIG. 1; FIG. 3 is a left side view of the fluid applicator tip of FIG. 1;

FIG. 4 is a right side view of the fluid applicator tip of FIG. 1; FIG. 5 is a back view of the fluid applicator tip of FIG. 1; FIG. 6 is a top view of the fluid applicator tip of FIG. 1; and, FIG. 7 is a bottom view of the fluid applicator tip of FIG. 1. Features shown in broken line in FIGS. 1, 2, and 7 are for illustrative purpose only and form no part of the claimed design.

1 Claim, 6 Drawing Sheets
